UNITED STATES PATENT OFFICE.

MARY C. PICKERING, OF GORHAM, ILLINOIS.

SHOE FASTENER.

Application filed January 11, 1926. Serial No. 80,640.

This invention relates to fasteners and more particularly to a snap fastener adapted for use in connection with a shoe in order to releasably retain a strap secured.

5 One object of the invention is to so construct the fastener that a portion thereof carried by the shoe securing strap may be easily and quickly snapped into locking engagement with a portion carried by the body 10 of the shoe.

Another object of the invention is to provide the fastener member carried by the shoe strap with a false head to be disposed against the outer face of the shoe 15 strap and represent a button or other fastener for securing the strap.

Another object of the invention is to so form the false head that it may serve as means for securing the strap carried fastener member to the strap.

This invention is illustrated in the accompanying drawing, wherein

Figure 1 is a perspective view of a slipper having its securing strap fastened 25 through the medium of the improved fastener;

Fig. 2 is an enlarged fragmentary sectional view taken on the line 2—2 of Fig. 1, and

Fig. 3 is a perspective view of the elements 30 forming the improved fastener.

The slipper 1 which has been illustrated in Fig. 1 is of a conventional construction and includes a strap 2 adapted to extend across the instep of the foot and have one 35 end releasably secured to the side of the shoe. While the improved fastener has been illustrated applied to a slipper, it will be understood that it could be applied to high shoes and also to low shoes other than the 40 specific type illustrated. The fastener which forms the subject-matter of this invention is indicated in general by the numeral 3 in Fig. 1 and referring to this figure it will be seen that when the strap 2 is secured the fastener has the appearance of a button which may be plain or of an ornamented type.

The parts or members comprising the improved fastener are illustrated in Fig. 3 and 50 include an ornamental head 4 which may be termed a false head, a member 5 which may be termed a socket member and a member 6 adapted to be secured to the body of the shoe at one side and snapped into 55 engagement with the socket member carried by the strap 2. The socket member 5

is formed of sheet metal and includes a base 7 having an upstanding peripheral wall 8, from the upper end of which extends an inwardly disposed annular flange 9 adapted to contact with the under face of the strap 2 when the socket member is secured to the strap. The socket 10 is disposed centrally of the base 7 and formed with side openings 11 adjacent its junction with the base 60 to receive the arms of the U-shaped clip 12. The clip 12 is formed of resilient metal and its arms pass inwardly through the openings 11 for locking engagement with the head of the member 6, as shown in Fig. 70 2. If desired, an opening 13 may be formed in the free end portion of the strap 2 to receive the socket 10 or this opening may be omitted and the portion of the strap 2 engaged by the socket forced upwardly when 75 the flange 9 is secured in close engagement with the under face of the strap.

The ornamental head 4 may be circular when viewed in top plan as illustrated or of any other desired shape and may be ornamented as illustrated in Fig. 3 or left plain. A flange 14 extends inwardly from the depending peripheral wall 15 of the ornamental head and from this flange 14 extend prongs 16 which are of sufficient length to 80 extend through the strap 2 with their lower free ends projected through slots 17 formed in the base 7 of the socket member 5 and clinched against its under face. It will, therefore, be seen that the prongs serve to 85 retain the ornamental head and socket member in firm gripping engagement with the upper and lower faces of the strap.

The member 6 which may be referred to as a stud includes a base 18 formed of sheet 90 metal and having depending prongs 19 of sufficient length to be passed through the leather or other material from which the shoe is formed and clinched against the inner face thereof. A neck 20 extends upwardly from the base 18 at its center and has engagement with the depending lug 21 of the head 22. This lug 21 tapers upwardly, as shown in Fig. 2, and, therefore, the head 22 is very firmly connected with the neck 20 and cannot be drawn upwardly out of engagement with the neck.

When the fastener is in use, the stud member 6 is secured to the side portion of the shoe and the socket member and false head or ornamental head are secured to the free end portion of the strap with the head 4

and socket member disposed in opposed relation to each other. After the shoe has been placed upon the foot, the strap 2 is drawn across the instep and the socket member disposed over the stud 6 and pressure applied to force the head 22 of the stud into the socket 10. The arms of the resilient latch or clip 12 engage the head 22 close to the neck 20 and, therefore, the head 22 will be firmly retained in the socket 10 and there will be no danger of the strap becoming detached. When it is desired to remove the shoe, it is merely necessary to grasp the strap at its free end and exert a pulling action in order to draw the socket member upwardly out of engagement with the stud. It will, therefore, be seen that the strap will be firmly but releasably held in place and that the use of a shoe hook or other similar implement is not necessary when fastening a shoe and also that the annoyance of a button or other similar fastener being lost is eliminated. While the fastener has been illustrated in connection with a shoe, it will be understood that other articles could have the fastener applied to them.

Having thus described the invention, I claim:

In combination with an article having separable sections, one section being adapted to be lapped over the other and having an opening formed therein, a snap fastener for securing said sections and including companion male and female members, said female member comprising a base disposed beneath the first section and engaging the under face thereof about the opening formed therein, a hollow head projecting from said base into said opening, said head being open at its bottom and forming a socket, an ornamental head engaging the upper face of the last-mentioned section about the opening formed therein, and prongs extending from said ornamental head through said opening with their ends projecting through openings in said base and clinched against the under face thereof, said male member secured to the other section and including a stud provided with a head adapted to be snapped into said socket.

In testimony whereof I affix my signature.

MARY C. PICKERING. [L.S.]
